UNITED STATES PATENT OFFICE.

JOSEPH W. SHERIDAN, OF QUINCY, ILLINOIS.

DESIGN FOR AN ICE-CREAM CONE.

Application filed January 10, 1927. Serial No. 20,326. Term of patent 14 years.

To all whom it may concern:

Be it known that I, JOSEPH W. SHERIDAN, a citizen of the United States, residing at Quincy, in the county of Adams, State of Illinois, have invented a new, original, and ornamental Design for an Ice-Cream Cone, of which the following is a specification, reference being had to the accompanying drawing, forming a part thereof.

I claim:

The ornamental design for an ice cream cone, as shown.

JOSEPH W. SHERIDAN.
